UNITED STATES PATENT OFFICE

150,465

DESIGN FOR A TOY AUTOGIRO

Howard F. Schmidt, San Diego, Calif.

Application July 5, 1946, Serial No. 131,331

Term of patent 7 years

(Cl. D34—15)

To all whom it may concern:

Be it known that I, Howard F. Schmidt, a citizen of the United States, residing at San Diego, in the county of San Diego and State of California, have invented a new, original, and ornamental Design for Toy Autogiro, of which the following is a specification, reference being had to the accompanying drawing, forming a part thereof.

In the drawings:

Figure 1 is a perspective view of a toy Autogiro, showing my new design;

Figure 2 is a top plan view;

Figure 3 is a front elevational view; and

Figure 4 is a side elevational view thereof.

I claim:

The ornamental design for a toy Autogiro, substantially as shown.

HOWARD F. SCHMIDT.
